UNITED STATES PATENT OFFICE.

HENRY E. SHAFFER, OF ROCHESTER, NEW YORK.

ACETYLENE-GAS BURNER.

SPECIFICATION forming part of Letters Patent No. 634,838, dated October 10, 1899.

Application filed April 8, 1899. Serial No. 712,267. (No model.)

To all whom it may concern:

Be it known that I, HENRY E. SHAFFER, a citizen of the United States, residing at Rochester, New York, have invented an Improved 5 Acetylene-Gas Burner, of which the following is a specification, reference being had to the accompanying drawings.

My invention relates to burners for acetylene gas having divergent arms provided with 10 diverging gas-passages and converging gas-exits and suitable air-passages to produce a flat flame, such as have heretofore been made entire of metal and also with metal arms and separable refractory tips.

15 My improved burner is fully described and illustrated in the following specification and the accompanying drawings, the novel features thereof being specified in the claims annexed to the said specification.

20 In the accompanying drawings, representing my improved gas-burner, Figure 1 is a side elevation. Fig. 1^a is an enlarged central vertical section of Fig. 1. Fig. 2 is a central vertical section. Fig. 3 is a partial side view 25 as seen from the direction of the arrows in Figs. 1 and 2. Figs. 4 and 5 represent a modification, the latter figure being a partial section on the line 5 5, Fig. 4.

My improved burner has a body consisting 30 of the hollow central stem A, having the gas-supply passage C. B B' are two hollow divergent arms having gas-passages D D', which are divergent and communicate with the minute convergent gas-exit orifices F F'.

35 A gas-supply tube is denoted by T.

E E' denote air-supply passages which, as shown in Figs. 1 and 1^a, are formed by boring through the material between the gas-exits and the outlet from the mixing-chambers N 40 N'. In Figs. 2 and 5 the air-passages E and E' are formed by boring from the rear of the arms B B' through the mixing-chambers and are contracted at H R and H' R', respectively.

In a modification represented in Figs. 4 and 45 5 two or more openings J J' J² lead the air from the passage E to the passage N, into which the gas is delivered from the orifice F.

The air-supply passages deliver air to air- 50 and-gas-mixing chambers N N' adjacent the gas-exits. The said chambers are partially bounded on their proximate sides by the faces

L L'. In use the burner produces a flat flame at O. To insure this form of flame, it is necessary that the jets of gas from the two exits accurately impinge as in other well-known 55 burners having opposite gas-exits adapted for the production of a single flat flame.

Especial nicety and accuracy of construction are required in acetylene-burners on account of the minute size of the gas-exits and 60 the consequent fineness of the gas-jets.

In burners of the same general form having refractory tips it has been found impracticable to cement the tips in the metal burner-arms so as to insure a suitable alinement of 65 the gas exits and jets. It is therefore the practice to light every such burner and adjust the tips after they have been cemented in the metal burner-arms by twisting or bending the arms by means of a suitable tool, and 70 thus experimentally secure an adjustment suitable for the production of the desired form of flame. The practice is general and is not only troublesome, but inefficient, for the reason that the high heat to which the burners 75 are subjected in use causes the twisted or bent metal to return toward its original position, whereby the gas-exits are thrown out of proper relation and the flame changed in form. 80

My improvement provides, by making the burner body and arms of one piece of non-metallic refractory material, that the gas-exits can be properly formed and arranged to produce the desired form of flame with certainty 85 and without testing and altering, as in the case of composite burners, and without danger of subsequent torsion by high heat. Such improved burners can also be made much cheaper than metal burners with refractory 90 tips.

It was suggested in Patent No. 618,239, granted me January 24, 1899, that burners of the character therein set forth might be made entire of refractory material. The present improvement relates to a distinct class of burners which are adapted for and heretofore have been provided with refractory tips inserted in divergent arms and having gas-exits directed toward each other to produce a flat 95 flame, the object being to remedy the before-mentioned defect in such burners. 100

Having thus described my invention, what I claim is—

1. The herein - described double - jet gas-
burner made entire of a single piece of refrac-
tory material with divergent arms having di-
verging gas - passages and converging gas-
exits and suitable air-passages all as set forth,
to insure and maintain the proper form of the
flame.
- 10 2. The herein - described double - jet gas-
burner made entire of a single piece of refrac-
tory material with divergent arms having di-
vergent gas - passages and converging gas-
exits and suitable air-passages all as set forth
15 to insure and maintain the proper form of the
flame, said air-passages leading to mixing-

chambers adjacent the gas-discharge open-
ings.

3. The herein - described double - jet gas-
burner made entire of a single piece of refrac-
tory material having divergent arms with di-
vergent gas - passages, convergent gas - exits
communicating therewith, air-and-gas-mix-
ing chambers in communication with the gas-
exits, and air-passages leading into the mix-
ing-chambers between the gas-exits and the
outlets from said chambers.

HENRY E. SHAFFER.
